[57] CLAIM

The ornamental design for a panorama tomographic X-ray unit, as shown and described.

DESCRIPTION

FIG. 1 is a front perspective view of a panorama tomographic X-ray unit, showing my new design;

FIG. 2 is a right side elevational view thereof;

FIG. 3 is a left side perspective view thereof;

FIG. 4 is a right side perspective view thereof, with the head in an alternate position;

FIG. 5 is an enlarged fragmentary right side perspective view thereof;

FIG. 6 is a top plan view thereof;

FIG. 7 is a bottom plan view thereof; and

FIG. 8 is a rear elevational view thereof.

The cord in FIGS. 1 and 8 is shown cut away for ease of illustration.
